UNITED STATES PATENT OFFICE.

DABNEY HERNDON MAURY, JR., OF PEORIA, ILLINOIS.

SYSTEM OF FLUID DISTRIBUTION.

SPECIFICATION forming part of Letters Patent No. 593,057, dated November 2, 1897.

Application filed November 25, 1895. Serial No. 570,014. (No model.)

To all whom it may concern:

Be it known that I, DABNEY HERNDON MAURY, Jr., a citizen of the United States, residing at Peoria, in the county of Peoria and State of Illinois, have invented certain new and useful Improvements in Systems of Fluid Distribution, of which the following is a full, clear, and exact description, reference being had to the accompanying drawing, forming part of this specification.

My invention relates to a new and improved system of fluid distribution which is more especially adapted for use in supplying towns and cities with water and in connection with oil and salt wells.

In many parts of this country as well as others, and particularly in the level prairie sections, the water-supply for the cities is generally obtained from wells, and great difficulty is sometimes experienced in securing a well with sufficient capacity for the purpose. In some instances great expense is entailed by reason of the necessity for having separate pumping plants, and in others different methods are employed for keeping up the supply. The same objections obtain in regard to oil and salt wells.

The object of my invention is to utilize a single pumping or power plant for bringing fluid from one or more separate and independent wells or other sources of supply to a convenient central point for distribution by said plant, whereby the supply at the central point can be maintained regardless of the level of the fluid in the separate sources of supply.

Another object of my invention is to maintain a constant and adequate source of supply which is fed automatically by other wells or supplemental sources of supply and all operated from a single pumping plant; and a further object is to pump or otherwise obtain fluid from the supplemental wells by means of power derived from the pressure of fluid coming from the pumping plant.

While my invention may be especially adapted for use in the level sections of the country, it is not in any way thereby restricted or limited in its application, and it may also be employed for other purposes and in other connections than for water distribution, including oil, brine, and other fluids.

I will now proceed to describe my invention as adapted for supplying water in connection with the accompanying drawing, which shows 55 a diagrammatic view of a simple embodiment of the invention.

It is to be understood that a reservoir may be dispensed with entirely, as it constitutes no part of my invention. The drawing, however, illustrates how my invention may be employed in connection with a reservoir which, for convenience, I have shown in a simple form.

A designates a main supply-well, B a suction-pipe leading to the pumping plant C, and D the force-main which leads from the pumping plant. In the drawing I have shown this force-main D connected with a reservoir E by a pipe F; but, as before stated, the reservoir may be omitted and the force-main lead from the pumping plant directly to the city or elsewhere. The reservoir outlet-pipe G may communicate with the force-main at any desired point when a reservoir is provided. 75

The main source of supply is usually a well, but a tank or other and different sources may be employed without affecting the beneficial results derived from the use of my invention. Any suitable form of pump may be used at 80 the pumping plant and any number of pumps may be employed therein. The force-main may lead directly from the pumping plant or from the reservoir, if there be one, or from both.

If only the single well A were used, the supply of water therein would be liable to fail, and in any event the power of the pumping plant would be maintained at an average far below its maximum, due to undue or excessive suction-lift. In order to keep the main well A always supplied with sufficient water, I provide any number of supplemental wells H, located at any distance from the main source of supply and connected therewith by an inclined pipe I. In the drawing only one of these supplemental wells is illustrated; but I may employ any number and they may be of any kind that may be found necessary or desirable, all of them being operated in substantially the same manner and communicating with the main well. 95

A water-motor J, of some approved construction, is arranged in or near to the sup-

plemental well, and it is driven by water under pressure from the pumping plant C, passing to the motor through the pipe K, which communicates with the force-main at some convenient point. It is not necessary that this pressure be taken from the force-main, for a separate pump may be provided at the pumping plant for the purpose of generating the pressure necessary for driving the motor.

10 A pump L is located in the supplemental well, and it is driven by the water-motor J through the medium of the shaft M or other suitable connections. The water lifted by the pump L passes through a pipe N into the inclined pipe I, and the water which passes through the motor J also passes into said pipe I through a pipe O and thence to the main well, or the water which passes through the motor may, if desirable, return to the well 15 through a separate pipe or be discharged from the motor J into the supplemental well. It will thus be observed that the water which has been pumped from the main well and used to run the water-motor J is conducted 20 back to the main well and is not wasted, while at the same time the water from the supplemental well is transferred to the main well. Obviously the water from the supplemental wells and also the water employed to lift the 25 water from said wells may be led directly into the suction-pipe B instead of into an open well, as illustrated in the drawing, such variation and many others that will readily suggest themselves to engineers being within the 30 scope of my invention.

The water used to drive the pump is saved, the supply in the main well is maintained, and only a single pumping plant required, for the pump and motor at the supplemental 40 well are driven practically from the pumping plant.

Suitable water-gates or stop-cocks are provided in the different pipes to regulate and control the water.

45 The particular arrangement and location of the different parts constituting my improved system are immaterial, and the connections herein described may be changed to suit varying conditions without departing from my 50 invention.

The advantages resulting from the use of my system must be manifest to those familiar with the art. I am enabled by this system to maintain a constant and sufficient source

of supply and utilize the pressure of water in the force-main to transfer water from a supplemental well to the main well. In referring to the main source of supply as a "well" it must not be understood that any special source of supply is necessary, for a tank or other source of supply would fulfil all the requirements of my invention.

Although I have described my invention in its application to a water-supply system, I would distinctly have it understood that this is but one of its many uses, and it may be employed with equally good results in connection with oil and salt wells and otherwise.

I am aware that changes in the details of my improved water-supply system and in the means employed for carrying out my invention may be made without departing from the spirit and without sacrificing the advantages thereof, and I therefore desire to reserve the right to make all such changes as fall within the scope of my invention.

Having thus fully described my invention, what I claim, and desire to secure by Letters Patent, is—

1. In a fluid-supply system, the combination with a main source of supply and a pumping plant, of one or more supplemental sources of supply connected by pipes or passages with the main source of supply, a pump operated by fluid under pressure from said plant and adapted to deliver the fluid of the supplemental source of supply into a passage leading back to the main source of supply; and a conduit for returning to the main source of supply the fluid by which the pump is operated, substantially as described.

2. In a fluid-supply system, the combination with a main well, a pumping plant connected therewith, a force-main, one or more supplemental wells, an inclined pipe leading from the supplemental well to the main well, a pump in the supplemental well adapted to deliver fluid into said pipe, a motor to operate said pump, a pipe leading from the force-main to the motor to deliver fluid thereto, and a pipe leading from the motor to the pipe communicating with the main well to deliver therein the fluid from the motor, substantially as described.
